(57) **CLAIM**

The ornamental design for a stand for solar panels, as shown and described.

DESCRIPTION

FIG. 1 is a bottom perspective view of a stand for solar panels according to a first configuration showing my new design;

FIG. 2 is a top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view taken from circle 9 in FIG. 1;

FIG. 10 is a left and top perspective view of a stand for solar panels according to a second configuration;

FIG. 11 is a right and top perspective view of FIG. 10;

FIG. 12 is a front elevational view of FIG. 10;

FIG. 13 is a rear elevational view of FIG. 10;

FIG. 14 is a left side elevational view of FIG. 10;

FIG. 15 is a right side elevational view of FIG. 10;

FIG. 16 is a top plan view of FIG. 10;

FIG. 17 is a bottom plan view of FIG. 10; and

FIG. 18 is a partial enlarged view taken from circle 18 in FIG. 13;

FIG. 19 is a partial enlarged view taken from circle 19 in FIG. 17;

FIG. 20 is a front perspective view of a stand for solar panels according to a third configuration;

FIG. 21 is a rear perspective view of FIG. 20;

FIG. 22 is a front elevational view of FIG. 20;

FIG. 23 is a rear elevational view of FIG. 20;

FIG. 24 is a left side elevational view of FIG. 20;

FIG. 25 is a right side elevational view of FIG. 20;

FIG. 26 is a top plan view of FIG. 20; and,

FIG. 27 is a bottom plan view of FIG. 20.

(Continued)

The dot-dash broken lines in the drawings depict the boundaries of the partial enlarged views that form no part of the claimed design.
